FRAMING DEVICE FOR PILE FABRICS AND METHOD OF USING SAME

Robert A. Hill and Julius Hertz, Rocky Mount, N. C., and Roy H. Niebling, Hackensack, N. J., assignors to Sidney Blumenthal & Co., Inc., New York, N. Y., a corporation of New York

Application October 3, 1956, Serial No. 613,734

7 Claims. (Cl. 206—51)

This invention relates to a framing device for pile fabrics and method of using same, and particularly to such a device in which a piece of pile fabric, as manufactured, may be rolled up for storage or shipment and to the method of putting the fabric in such a frame.

As distinguished from flat fabrics which can be rolled into a compact body, it is necessary, in the case of pile fabrics, to maintain some space between each successive layer of the roll in order to protect the pile from being wrinkled or crushed. The method which has been employed for many years to accomplish this made use of a multiplicity of hooks mounted on a frame so that the fabric could be suspended by the selvage from hook to hook in an expanding square or rectangular pattern. This method requires very tedious hand labor to perform, besides employing relatively expensive hooks and frames.

It is an object of the present invention to provide means for rolling a pile fabric rapidly and easily into spiral form with the successive layers evenly spaced. It is proposed to attain this object by the use of zipper type fasteners, as set forth below.

A further object of the invention is to provide apparatus specially designed for rolling up a piece of pile fabric and for forming a strong and convenient package for shipment or storage, and the method of doing so.

A practical embodiment of the invention is shown in the accompanying drawings, wherein:

Fig. 1 represents a perspective view of a roll of pile fabric as formed into a completed package, parts of the package being broken away.

Fig. 2 represents an elevation of one of the end discs to which an edge of the fabric is to be attached.

Fig. 3 represents a detail section on the line III—III of Fig. 2,

Fig. 4 represents a detail perspective view of an edge of the fabric prepared for rolling.

Fig. 5 represents a detail perspective view, on an enlarged scale, of a portion of the package, parts being broken away.

Fig. 6 represents a detail perspective view of a portion of a modified form of end disc.

Fig. 7 represents a view, partly in vertical section and partly in elevation, of a form of apparatus adapted for use in rolling a piece of pile fabric as proposed herein,

Fig. 8 represents a detail diagrammatic plan view of the slider-pulling arm as used in the rolling of the fabric, and

Fig. 9 represents a detail end view, on the line IX—IX of Fig. 7 and on a larger scale showing one of the latch fingers.

Referring to the drawings, the end disc 1 is formed of a suitable stiff and strong material such as wood or metal. On one of its faces is attached, as by stapling or adhesive, the tape 2 bearing zipper type fastener elements 3, the tape being at least as long as the piece of pile fabric to be rolled, and being mounted on the disc 1 in a close spiral starting near the middle of the disc, as clearly shown in Fig. 2. Another disc 1' designed to

2

to constitute the opposite end of the roll or package is similarly formed except that the spiral is reversed.

When a piece of pile fabric has been woven and is ready to be rolled it is run through stitching devices which baste on each selvage a tape 4 bearing fastener elements 5 which are complementary to the elements 3 and adapted to be engaged therewith. Referring to Fig. 4, the pile portion of the fabric is indicated at 6, the selvage at 7 and the basting stitches at 8. As an alternative, the fastener tape 10 may be heat sealable so that it can be applied to the selvage continuously by a hot roller.

In order to form a rolled package of the fabric, a pair of end discs 1, 1' are mounted in rotating chucklike driving heads 9, 9' (Fig. 7) where they are held in any convenient manner as, for instance, by means of spring-actuated latch fingers 10 accommodated in slots 11 formed around the periphery of each disc. The heads 9, 9' are supported on suitable stands and are motor driven in synchronism in the same direction, a motor 12 being shown, while the drive connection to the opposite head is omitted. The head 9 is shown as being mounted on a carriage 13 which can be moved, as by the hand wheel 14 and screw 15, to adjust the spacing between the heads 9 and 9'. Each head may be provided with a manually operated latch release plate 16, for instance, adapted to press in the rear ends 10' of the latch fingers and thus release them all simultaneously. The specific form of the mechanisms just described may evidently be varied in many respects while still serving the same purpose.

In operation, the end discs are mounted in the driving heads, as stated, and are spaced somewhat closer together than the width of the fabric to be rolled. A piece of pile fabric provided with fasteners on both selvages has its fasteners engaged with the inner ends of the fastener strips on the discs and with the sliders 17 which are adapted to cause interengagement of the respective fastener strips. Each slider is then attached, as by a cord or wire 18, to a holding arm 19 in order to keep the sliders from rotating with the discs, and the heads are rotated in order to secure the fabric edges automatically to the discs in a slightly loose spiral roll. Upon completion of the roll, the fastener ends or the sliders are secured by staples or otherwise to keep them from reopening. The carriage 13 is moved outwardly to take up the slack across the width of the fabric and a wrapper 20 of corrugated board or the like is wrapped around the roll of fabric and fastened at its edges around the edges of the end discs, as clearly shown in Figs. 1 and 5. The longitudinal seam may be sealed by means of tape or the like. The latch fingers 10 are then moved to free the discs, the driving heads are further separated, and the strong, compact cylindrical package of fabric is ready for shipment, storage, etc.

In order to unroll the fabric, or any part of it, the package can be placed on an axial shaft passing through the holes 21 in each end disc and provided with stops to prevent too much loosening of the roll, the sliders being held by hand and moved in the "unfastening" direction as the roll is turned, or the sliders can be attached to arms such as the arms 19 mentioned above. If the entire roll of fabric is to be unrolled, the sliders can be removed entirely and the fasteners will strip open as the fabric is unrolled.

If available, apparatus similar to that used for winding the roll could be used in an obvious manner for unwinding it. When a length of fabric is unrolled for use, the fastener tape along its selvages can be removed merely by taking out the stitches 8 and it can be saved in its full original length for re-use or can be cut off and discarded.

A modified form of end disc is shown in Fig. 6, this disc being formed from a spiral "sandwich" of the fastener tape 22 with an elongated strip of filler material 23, such

3

as corrugated board or plastic, wound tightly together and cemented by a suitable adhesive into a monolithic unit. This unit, as shown, is further strengthened by being mounted on a wood or metal backing disc 24 similar to the disc 1, but the sandwich structure alone may be strong enough to serve its purpose in some instances and with some materials, as for instance, and for light packages. The completed package, made as set forth, depends for its rigidity on the cylindrical outer covering, which may be further strengthened by the provision of longitudinal reinforcing strips. If desired, the end discs could be mounted rigidly or adjustably on an axial tube or shaft of fixed or variable length, such as telescoping tube sections connected by jack means for varying the spacing of the discs. If the end discs are fixedly mounted on an axial tube of strong paper, for instance, the spacing of the discs should be such as to permit rolling the fabric with the least possible transverse slack; while such semi-tight rolling may be more difficult than the slack rolling described above, it permits use of a simpler supporting and rolling mechanism and produces a stronger final package. While metallic or solid plastic zipper elements are suggested by the drawings and text above, it will be understood that cooperating fastening elements of other types, such as those comprising interlocking continuous grooves, could be substituted if desired, and other details of form, construction and arrangement are likewise subject to modification within the scope of this invention.

What we claim is:

1. A pile fabric package comprising, a pair of end discs in facing parallel relation, a continuous fastener element in strip form fixed spirally on each of the opposite facing surfaces of said discs, an elongated web of pile fabric having a continuous fastener element in strip form fixed along substantially the entire length of each selvage, the fastener elements on the discs being complementary to those on the selvages and engaged therewith so that the web is held in spirally rolled formation with the convolutions of the web spaced from each other,

and a cylindrical wrapper secured at its ends to the peripheries of said discs.

2. A package according to claim 1, in which the end discs are solid and in which the strips of fastener elements are secured to one flat surface of each disc.

3. A package according to claim 1 in which each end disc includes a spirally laminated body and in which the strips of fastener elements are anchored in said laminated bodies.

10 4. A package according to claim 1, in which the means for holding the discs parallel and spaced comprises a cylindrical wrapper secured at its ends to the peripheries of said discs.

5. The method of packaging pile fabric which includes, 15 providing a pair of end discs each having a continuous fastener element in strip form secured spirally on one face thereof, attaching to each selvage of an elongated web of pile fabric a continuous fastener element in strip form complementary to said first-named fastener elements 20 and engageable therewith, holding said discs parallel and spaced by a distance not substantially greater than the width of said fabric web, engaging corresponding ends of the selvage fastener strips with the inner ends of the disc fastener strips, rotating said discs, and causing said complementary fastener elements to interengage progressively along the length of said fabric web.

6. The method according to claim 5, which includes, 25 moving said discs apart to tighten the fabric web across its width, and fixing said discs in said spaced apart position.

7. The method according to claim 5 which includes applying a cylindrical protective wrapper around the outside of the fastener-supported fabric and securing said wrapper to the peripheries of said discs.
